UNITED STATES PATENT OFFICE.

JOHN D. STANDEFER AND JAMES H. STIDHAM, OF DOOLEY, VIRGINIA.

WASHING MACHINE.

Application filed March 1, 1922. Serial No. 540,200.

To all whom it may concern:

Be it known that we, JOHN D. STANDEFER and JAMES H. STIDHAM, citizens of the United States, residing at Dooley, in the county of Wise and State of Virginia, have invented certain new and useful Improvements in a Washing Machine, of which the following is a specification.

The present invention relates to a washing machine and has for its principal object to provide a simple and efficient device which may be manufactured at a comparatively low cost and which will be reliable in operation and well adapted to the purpose for which it is designed.

Another important object of the invention is to provide an agitating mechanism which will move the clothes in the water so as to cleanse the dirt therefrom without tending to tear or otherwise injure them.

Another object of the invention is to provide a two-compartment receptacle one of which takes the place of a boiler and the other is the washing receptacle proper.

A still further object of the invention is to provide an efficient spraying mechanism whereby a supply of clean water may be delivered from the boiler receptacle to the washing receptacle.

With the above and numerous other objects in view as will appear as the description progresses the invention resides in certain novel features of construction, and the combination and arrangement of parts as will be hereinafter more fully described and claimed.

In the drawing:—

Figure 1 is a vertical section through the device,

Figure 2 is a horizontal section taken therethrough,

Figure 3 is a vertical transverse section taken therethrough at right angles to the section shown in Figure 1,

Figure 4 is a plan view of one of the agitating members,

Figure 5 is a detailed perspective of a portion of one of the agitating members,

Figure 6 is a detailed perspective of the spraying spout, and

Figure 7 is a detailed perspective of the lower portion of the spouting device.

Referring to the drawing in detail it will

be seen that the receptacle consists of the boiler compartment 1 and washing compartment 2. The washing compartment 2 is within the boiler compartment 1 as is shown to advantage in Figures 1 and 2 wherein it will be seen that the boiler compartment is substantially U-shaped and that the compartment 2 is situated within the legs thereof. A tube 3 is situated in each leg of the boiler compartment 1 and communicates at its bottom with a casing 4 having a reduced bottom 5 provided with a plurality of apertures for allowing the water in the boiler compartment 1 to penetrate therethrough so as to fill the casing 4 and the tube 3. These tubes 3 extend above the receptacle and terminate in a spraying spout 7 which extends over the washing compartment 2 and is provided on its bottom with a plurality of apertures. In one leg of the boiler compartment 1 there is journaled longitudinally thereof a crank shaft 8 provided with a plurality of crank members 9. The bottom end of this crank shaft 8 is journaled at 10 in the bottom of the boiler compartment 1 and the upper end thereof is journaled in a bar 11 which extends transversely of the upper end of the leg in the compartment 1. This crank shaft 8 passes through the bar 11 and has keyed upon its terminal a beveled gear 12 which is in mesh with a beveled gear 13 keyed on the shaft 14 which is journaled in the brackets 15 and 16. A drive pulley 17 is situated on the shaft 14 so that by rotation thereof by any suitable means the shaft 14 will be rotated so as to rotate the beveled gear 13 which in turn rotates the beveled gear 12 so as to impart a rotary motion to the crank shaft 8. A plurality of pitman rods 20 are slideable through the walls of the compartment 2 and are connected to the cranks 9 so as to be reciprocated thereby. A plurality of agitating members are situated in the compartment 2 and are actuated by the pitmans 20. It will be noted that cross pieces 21 are pivotally connected to the inner end of the pitman rod 20 for supporting the agitating mats 22 which are formed from a series of corrugated strands of wire which are held between the cross bars 21 and 22'. The cross bar 22' is held within a clamp member 23 which is held together by the set screws 24.

This clamp member 23 is mounted on rods 25 which are slidably mounted in the opposite wall of the compartment 2. It will thus be seen that the crank shaft 8 will reciprocate the corrugated mats 22 through the intermediary of the pitmans 20.

It will be noted in Figure 2 that the bottom end of the compartment 2 is provided with a drain cock 27 so that the dirty water 10 which settles therein may be drained therefrom while a supply of fresh boiling water is being supplied through the tube 3.

In using the device we place the water which has previously been supplied with 15 soap or the like in the boiler compartment 1 which is then placed upon a stove or some other heating means and when the same comes to a boil, the water will be forced through the casings 4, and tubes 3 into the 20 washing compartment 2. The clothes may be placed upon the mats so that the same may be agitated through the water as it is sprayed thereon. It will be understood that by providing the clamp 23 these mats may 25 be pivoted so that the clothes may be piled on the respective mats starting with the bottom 1.

Although we have described our invention with some degree of particularity, it is to be 30 understood that this has been done only by way of example and that numerous changes in form, proportion, and in the combination and arrangement of parts may be resorted to without departing from the spirit of the 35 invention as hereinafter claimed.

Having thus described our invention what we claim as new is:—

1. A device of the class described including a tank having a series of apertures arranged in oppositely disposed pairs, rods 40 slidably mounted through said apertures, flexible mats supported by said rods, a crank shaft for operation of one series of rods for imparting reciprocatory motion to the mats, and means for rotating the crank shaft. 45

2. In combination, a receptacle provided with an outer compartment and an inner compartment, a tube disposed in the outer compartment terminating at one end adjacent the bottom of the outer compartment 50 and at its other end adjacent the top of the inner compartment, a spraying spout leading from the top of the tube over the inner compartment, a clothes supporting member disposed within the inner compartment, and means for moving the clothes supporting member to and fro in the inner compartment whereby when liquid is heated in the outer compartment it may be delivered through the tube and sprayed over clothing 55 supported by the clothes supporting member as it moves all in the manner and for the purpose specified. 60

In testimony whereof we affix our signatures in presence of two witnesses.

JOHN D. STANDEFER.
JAMES H. STIDHAM.
